ROLLER SKATE

Frank J. Wagner, Franklin Square, N. Y., assignor
of one-half to Carroll M. Bierman, Franklin
Square, N. Y.

Application February 11, 1948, Serial No. 7,662

6 Claims. (Cl. 280—11.28)

1.

This invention relates to roller skates in general and more particularly to skates suitable for performers when executing intricate free style and jumping acrobatics.

With skates heretofore in use, especially when executing free style and jumping acrobatics, during which the axles of the truck were required not only to incline radially relative to the longitudinal axis of the skate but also angularly relative to the vertical axis of the skate, control of the skate or skates was temporarily lost by so-called sub-curves resulting when the truck did not promptly return to normal. According to the present invention, delicate adjustments can be made to suit the power and weight of the particular skater and yet insure return of the truck back to normal position immediately after the skate had left the supporting base, such as the floor of the rink, stage, or the like, so that the performer may have perfect control of his skates at all times.

These and other features, capabilities and advantages of the present invention will appear from the subjoined detailed description of one specific embodiment thereof illustrated in the accompanying drawings, in which:

Fig. 1 is a plan view.

Fig. 2 is a side elevation.

Fig. 3 is a front elevation.

Fig. 4 is a section on the line 4—4 of Fig. 3.

In the embodiment shown, the skate consists essentially of the bar 1, preferably an aluminum casting forming the hanger or frame to which are secured the metal heel plate 2 and metal sole plate 3. Preferably disposed as indicated, centrally of the area where the weight from the heel of the skater is transmitted to the bar 1 and centrally of the area where the weight of the sole of the skater is transmitted to the bar, there are secured the bearing blocks 5 and 6, respectively, the blocks 5 and 6 consisting essentially, as shown in Figs. 2, 3 and 4, of blocks, hexagonal in outer contour, provided with a stud 1 screw threadedly connected to the bar 1, and a conical recess 8 with a blunt apex. To the front of the block 5 and to the rear of the block 6, there are screw threadedly connected to the bar 1, the king pins 9 and 10, respectively, which in the present instance are threaded about half way down from the upper end as shown and each provided with a diminished threaded lower projection, see the projection 11 for the pin 9. The block 5 and king pin 9 constitute a rear pair and the block 6 and king pin 10 a front pair of elements to which the front and rear trucks are connected. The front

2.

and rear trucks are substantially identical, and therefore the illustration in Fig. 4 of the rear truck and description of the same will also suffice for the front truck.

5 Each of these trucks consists essentially of a plate 13 having an outer enlarged portion 14 and an inner diminished portion 15, the outer enlarged portion 14 having a horizontally extending opening 16 to fixedly receive the axle 17, 18 for the roller skate wheels, such as the wheels 19 for the rear axle 17 and the wheels 20 for the front axle 18. The enlarged portion 14 is also provided with a smooth vertically extending opening 21 and the diminished portion 15 with the smooth vertically extending opening 22.

In the opening 21 there is slidably mounted the stud 23 of the floating pin 24 which has a collar 25 and a conical upper end 26. The conical upper end 26 in dimension is much smaller than the conical recess 8 so that it may freely rock therein while the apex of the upper end 26 engages the apex of the recess 8. Between the collar 25 and the upper face of the enlarged portion 14 there is mounted on the stud 23 the main weight receiving and cushioning rubber washer 27 which in the present instance is provided with the cap 28 disposed between the collar 25 and the washer 27 to protect the washer 27 from mushrooming.

30 The king pins 9 and 10 are secured in position in the bar 1 by the lock nuts 29 and 30, respectively, and serve in the present instance not only to anchor the trucks in place but also as stabilizers. As an instance, the smooth part of the king pin 9, 10 is slidably mounted in the opening 35.

22. The upper face of the diminished portion 15 is recessed to receive the lower end of the large rubber washer 31 which is mounted on the king pin 9, 10. The upper end of the washer 31 is preferably provided with a cap 32 which is disposed between the washer 31 and the stabilizer bar 33 through which the king pin 9, 10 extends. Above the stabilizer bar 33, the king pin 9, 10 is provided with the large adjusting nut 34 which cooperates 40 with a lock nut, such as the shake-proof lock nut 35 at the lower end of the king pin 9, 10 to compress the washer 31 and in turn to adjust the yieldability and elasticity of return to normal position of the truck associated therewith characterized by the plate 13 and associated parts. From the foregoing it will be seen that since the engagement of the conical end 26 with the apex of the conical recess 8, constituting the fulcrum, is disposed between the axle 17, 18 and the king pin 9, 10, respectively, that the weight of the

skater will never be transmitted to the rubber washer 31, that the weight of the skater will only be received by the rubber washer 27, and that in turn the washer 31 will only act as a stabilizer which will quickly resume its normal shape after distortion, to return the truck characterized by the plate 13 to normal position after a skate has left the ground, and that the reluctance to distortion can be adjusted to suit the power and weight of the performer. In other words, the greater the power and weight of the performer, the more easily with a given tension on the washer 31 will the distortion be effected, so that the tension resulting in a greater reluctance to distortion must ordinarily be increased as the power and/or weight of the performer increases.

The stabilizer bar 33 extending as it does from one king pin 9 to the other king pin 10 and being anchored in position to each king pin will not rotate with the washer 31 and therefore cannot affect the adjustment of the adjusting nut 34 after it has once been set. In other words, the bar 33 serves as a buffer to protect the adjusting nut 34 from being disturbed once it has been set, no matter how vigorous the distorting forces nor with what rapidity the distorting forces are transmitted to the washer 31.

The lock nut 35 at the lower end of the king pin 9, 10 facilitates ready assembly and removal of the truck characterized by the plate 13 and associated parts since it will only be necessary to remove the nut 35, and the entire truck characterized by the plate 13 and associated parts up to the large adjusting nut 34 can be readily and with facility lifted from the king pin 9, 10.

Preferably as shown, a washer about one-eighth inch thick by three-quarters of an inch in diameter is mounted on the king pin 9 and interposed between the lock nut 35 and the lower face of the diminished portion 15 of the plate 13, the washer 36 serving both as a wearing element between the lock nut 35 of the plate 13 and also to effectively cover the opening 22 so that the washer 36 will support the lock nut 35, with the washer 36 in turn resting on the lower face of the plate 13 surrounding the opening 22.

It is obvious that various changes and modifications may be made to the details of construction without departing from the general spirit of the invention as set forth in the appended claims.

I claim:

1. In a roller skate, the combination of a hanger having two downwardly extending blocks with conical recesses therein, two king pins between said blocks, each king pin disposed adjacent to one of said blocks, a pair of wheel trucks, each truck freely movable and slidably mounted on one of said king pins and rockably mounted in its adjacent conical recess, a stabilizer bar extending from one king pin to the

other, a stabilizing rubber washer mounted on each king pin and disposed between each truck and said bar, and an adjusting nut on each king pin engaging said bar and functioning to transmit the required tension on its associated rubber washer.

2. The combination as set forth in claim 1 in which a floating pin is slidably mounted on each truck and provided with a collar and a conical upper end, a rubber washer mounted on said floating pin and interposed between said collar and the truck, each conical end engaging the apex of a conical recess and enabling the truck thereby to rock relative to said hanger.

3. The combination set forth in claim 2 in which each wheel truck has a wheel carrying axle and each floating pin is disposed between its associated king pin and its associated axle, with the axles disposed at the outer ends of the trucks to enable the weight of the skater to be received by the rubber washer on said floating pin and to enable the rubber washer on said king pin to stabilize or return the truck to normal position after a distortion force has ended.

4. In a roller skate, the combination of a hanger having a block extending down therefrom and provided with a conical recess, a king pin fixed to said hanger, a floating pin rockably engaging said conical recess, a truck slidably mounted on said floating pin and slidably and rockably mounted on said king pin, a resilient washer mounted on said king pin, and an adjusting nut for regulating the tension on said washer and thereby the reluctance of said truck to rock relative to said king pin.

5. The combination set forth in claim 4 in which the floating pin has a collar and an upper conical end rockably engaging the conical recess in said block, and a rubber washer is mounted on said floating pin and interposed between said truck and said collar to receive the weight of the skater.

6. The combination set forth in claim 5 in which the truck has a wheel carrying axle and the floating pin is disposed between said axle and said king pin to facilitate transmitting the weight of the skater to the rubber washer on said floating pin.

FRANK J. WAGNER.
